UNITED STATES PATENT OFFICE.

THERON L. HILES, OF NILES, MICHIGAN.

GASEOUS-FUEL SUPPLY SYSTEM.

Application filed June 20, 1921. Serial No. 478,804.

To all whom it may concern:

Be it known that I, THERON L. HILES, a citizen of the United States, residing at Niles, in the county of Berrien and State 5 of Michigan, have invented certain new and useful Improvements in Gaseous-Fuel Supply Systems, of which the following is a specification.

The invention relates to a fuel supply 10 system which is adapted for use primarily in the industrial arts, and has more particular reference to a means for supplying fuel in fluid form, such as a mixture of fuel gas and air, for efficient combustion.

15 Among the methods now commonly employed for effecting the mixture of air and gas for combustion purposes are what are generally known as the two-pipe system, the atmospheric system and the one-pipe system.

20 In the two-pipe system the air and gas are supplied by means of two separate pipes, both being under pressure and controlled manually. In the atmospheric system, the gas only is supplied under pressure, the supply 25 of air being effected by induction, and both the supply of air and gas are controlled manually. In the one-pipe system, a primary mixture of air and gas is supplied by means of a single pipe, and a sufficient quantity of air is supplied at the burner by induction to render the mixture combustible.

In this case also the relative proportion of the air and gas is controlled by manually operable means. As a result of such manual control in the prior systems, great skill is required on the part of the operator or attendant in producing a combustible mixture having the proper ratio of air and gas. Moreover, it is impossible, even with the exercise of such skill, to effect such mixture with substantial uniformity. Consequently such prior systems are incapable of operation with a high degree of efficiency.

The principal object of the present invention is to produce a system for supplying a fluid or gaseous fuel, in which one of the elements composing the fuel is supplied under pressure, as in the atmospheric system, and the other element is supplied in a measured or proportional volume through a positive movement thereof effected through the utilization of a portion of the force of the element under pressure.

Another object of the invention is to produce such a device for mixing air and gas

in a predetermined ratio which is operable wholly automatically and hence is not dependent upon the skill of the attendant nor subject to the inaccuracies which unavoidably accompany the manual control. 60

A further object is to provide such a device which will effect such mixture at the burner in any desired volume and will automatically maintain a predetermined ratio between the elements constituting the mixture for all volumes consumed. 65

A further object of the invention is to produce a fluid fuel supply system in which the mixture may be supplied at any desired number of points or stations and wherein 70 each station constitutes a unit which is individually adjustable, and is wholly independent of and not affected by the operation or adjustment of other units, thus lending flexibility to the system such that it is 75 capable of many and diversified uses.

With the above objects in view, the invention contemplates the utilization of power stored in one of two fluid elements to accomplish a positive flow of a proportional 80 volume of the other element. This is accomplished in the present instance by the use of a rotary impeller having a series of turbine blades arranged to receive the impact of the element under pressure prior to its final discharge from its conductor and in advance of the meeting and mixing of the two fluids. The impeller, through the medium of a second series of blades or vanes, acts upon the second element surrounding 85 said conductor, to propel it forwardly for intermixture with the element under pressure. The speed of rotation of the impeller is dependent upon the force of the impact upon the turbine blades. Consequently, by 90 varying the volume of the element under pressure discharged, the volume of the second element is also controlled so as to maintain the desired predetermined ratio between 95 the elements for all volumes of the mixture 100 consumed.

In the accompanying drawings, wherein I have shown but a single embodiment of the invention, it will be understood, however, that changes in arrangement, form, construction and proportions may be made by those skilled in the art without departing from the spirit and scope of the invention as expressed in the appended claims.

In Figure 1 of the drawings I have shown 110

diagrammatically a gaseous fuel supply system embodying my invention. Fig. 2 is a fragmentary vertical sectional view through my improved means for effecting the mixture of air and gas. Figs. 3 to 6 are transverse sectional views taken substantially in the planes of lines 3—3, 4—4, 5—5, 6—6 of Fig. 2. Fig. 7 is a rear side elevation of a fan wheel constituting the measuring and mixing device. Figs. 8 and 9 are detail views in section taken respectively in the planes of lines 8—8 and 9—9 of Fig. 7. Fig. 10 is a rear end view of a portion of the means for controlling the volume of gas discharged for consumption.

Referring first to Figure 1, 14 designates generally a compressor of any usual or preferred form, and 15 a main having branches 16 leading respectively to one or more stations designated generally A, B and C.

At each of said stations there is provided a device shown particularly in Fig. 2 which is operable entirely automatically to control the flow of one of the elements constituting the gaseous fuel in a predetermined proportion to the volume of the other element which is subject to manual control for varying the volume of the mixture to be consumed. The device comprises generally a gas tube 17 communicating with a branch pipe 16, and surrounded by an air tube constituting an annular casing 18. Said casing provides an air passageway 19 around the gas tube 17, and a passageway 20 into which the gas is discharged for mixture with the air. 21 designates generally an impeller which I have herein designated for convenience a "turbo fan wheel" because it embodies two or more sets of fans or blades of which one set are turbine blades arranged to receive the impact of one fluid body, which is under pressure, so as to be rotated thereby, and of which the other set are fan blades which in the rotation of the device produce a flow of another fluid body not under pressure. In the present instance this turbo fan wheel is adapted to be actuated by the flow of gas through the gas tube 17, and is capable in turn of acting positively upon the air in the passage 19 to move or propel a metered or measured quantity thereof forwardly in the passageway 19 and into the passageway 20. 22 indicates a manually operable means for controlling the volume of gas discharged from the nozzle and hence the volume of the gaseous mixture discharged for consumption.

The gas tube 17 is preferably especially constructed, as by being cast, and has a rear depending portion 17^a which is connected with the branch pipe 16 by means of a valve fitting 23 having a valve of any preferred form operable by means of a hand wheel 24 to control the flow of gas into the nozzle.

65 The annular casing or air tube 18 is

mounted upon the gas tube 17 in concentric spaced relation, to provide the annular passageway 19, the casing being made of substantially larger diameter than the tube 17. Thus the circular plate 25 encircles the tube 17 and is secured thereto by means of screws 26 entered through an outturned annular flange 27. Near the periphery of the plate the casing 18 is secured to the plate by means of bolts 28 entered through an annular outturned flange 29 at the rear of the casing 18. A suitable number of apertures 30 are provided in the plate 25 adjacent the tube 17 to provide for the entrance of air into the passageway 19. Preferably the forward end 80 of the tube 17 is restricted in diameter so as to form the frusto-conical discharge nozzle or tip 31, and the forward end of the casing 18 is shaped as at 32 so that the passageway 20 constitutes a Venturi tube. This construction facilitates the discharge of the mixture to the point of combustion at a velocity sufficient to prevent back-flashing, and also serves to effect a more intimate mixture of the gases.

Herein the nozzle 31 is constructed separately from the gas tube 17 and is mounted with respect to the tube in slightly spaced relation so as to accommodate between it and the forward end of the tube the fan 95 wheel 21. Thus, within the tip 31 there may be cast a spider 33 centrally apertured to receive a bolt 34 the inner end of which is screw-threaded into a disk 35, which latter in turn is screw-threaded into the extreme forward end of the gas tube 17. The spider is preferably extended rearwardly to provide a bearing for the forward face of the wheel. To provide an additional support for the nozzle 31, a plurality of radial set screws 36 may be employed as shown in Fig. 6.

Herein the turbo fan wheel 21 constituting the impeller is made from a disk of sheet metal or the like, of a diameter corresponding substantially to the internal diameter of the air tube 18 at the forward end of the gas tube 17. A central aperture 37 is provided in the disk for receiving the bolt 34 upon which the wheel is rotatably mounted. Near its center the disk has formed therein a plurality of inclined blades 38 which constitute turbine blades adapted when gas is discharged from the tube 17 to impart rotation to the fan wheel. Near its periphery the disk is provided with a plurality of oppositely disposed blades constituting fan blades 39. The latter are adapted upon rotation of the fan wheel to engage a measured quantity of air from the passageway 19 and propel it forwardly in a positive manner rather than by induction in the ordinary way, into the passageway 20, the volume depending upon the speed of rotation of the wheel and hence upon the 130

pressure and volume of the gas discharged against the turbine blades 38. It will be understood that these blades 38 and 39 are relatively proportioned or calibrated so that 5 for a given volume of gas discharged against the blades 38 a predetermined proportion of air will be drawn and forced through the fan wheel by the blades 39. Consequently, when the volume of gas is controlled, 10 the device operates automatically to maintain the predetermined ratio between the constituent elements of the mixture.

The controlling means 22 for determining the volume of gas to be discharged from 15 the gas tube 17 comprises a valve disk 40 having a plurality of ports therein adapted to coact with a plurality of ports in the stationary disk 35 in the forward end of the air tube 18. Referring to Fig. 4, the disk 20 40 as herein shown, has four ports 41, 42, 43, and 44, and the disk 35 (Figs. 2 and 10) has two ports 45 and 45^a with which the ports 41 to 44 are adapted to register. The port 45^a is herein made twice the size of the 25 port 45, and said ports 41 to 44 are arranged in a manner hereinafter set forth so that in various positions of the disk 40 various quantities of gas are discharged through the ports 45 and 45^a. The latter, it will be 30 noted by reference to Fig. 2, are preferably inclined inwardly and forwardly so as to direct the flow of gas against the turbine blades 38 in the most effective manner and thus more effectually to accomplish the rotation of the wheel 21 through the force of 35 compression transmitted through the gas.

The means herein shown for operating the valve disk 40 comprises a stem 46 rigid with the disk and extending rearwardly 40 through the tube 17, the latter being provided at its rear end where it connects with the depending portion 17^a, with a bearing 47. A hand wheel 48 is fixed on the rear end of the stem and a screw 49 is mounted 45 in the bearing and engages at its inner end in an annular groove 50 in the stem whereby to hold the stem against longitudinal movement in its bearing. A suitable stuffing box 51 may be provided around the stem.

50 Preferably means is provided for enabling the attendant to adjust the valve means 22 so as to accomplish accurately the discharge of any desired volume of gas for consumption. This means may comprise 55 a notched wheel 52 fixed upon the stem 46 near its rear end, with which a spring latch member 53 secured upon the bearing 47 is adapted to coact. To this end the wheel 52 has a plurality of notches, corresponding in 60 number to the ports 41 to 44 in the valve disk 40, and designated 41^a, 42^a, 43^a and 44^a. These notches are adapted to coact with a knife edge 54, and together with the ports 41 to 44 in the valve disk are relatively arranged so that when the notch 41^a is en-

gaged by the latch member both ports 45 and 45^a are closed; when the notch 42^a is engaged by the latch member, the port 45 is opened; when the notch 43^a is engaged by the latch member, the port 45^a is opened; 70 and when the port 44^a is engaged by the latch member, both the ports 45 and 45^a are uncovered. The sizes of these ports 45 and 45^a are, it will be understood, properly portioned so as to emit under a given pressure 75 predetermined volumes of gas, and it thus becomes possible by simply manipulating the hand wheel 48 of the valve controlling means to regulate accurately the volume of gas discharged for consumption, three 80 variations being herein provided for. The resulting operation of the turbo-fan wheel serves to measure automatically the amount of air required for intermixture with the gas to produce a combustible mixture of 85 the proper air and gas ratio.

It will be seen that I have produced a means for supplying gaseous fuel for combustion purposes which is of a very efficient as well as practical character. The air is 90 positively impelled forwardly in a measured or metered volume proportional to the volume of gas discharged. The manual control of the ratio between the air and gas constituting the combustible mixture, which is 95 necessary in devices of the prior art, is entirely eliminated as are also the uncertainties and inaccuracies necessarily attendant upon the manual operation. Also, the 100 volume of the combustible mixture consumed is capable of being readily varied without upsetting the predetermined ratio.

In the industrial arts it frequently is 105 desirable that in a single system, a plurality of stations may be provided at which work of a different character is performed and hence having different requirements as regards the combustion of fuel. Thus it will be apparent that where the combustion takes 110 place in the open air a lesser amount of air need be mixed with the fuel gas for the efficient combustion thereof than in a case where the combustion occurs within a closed furnace. In my improved system, the 115 burners at the several stations may be readily made to conform to the varying conditions which may exist. This is accomplished by the use of turbo fan wheels having their blades properly coordinated to effect the relative movement of the gases constituting the mixture which may be rendered desirable by the peculiar operating conditions. It will thus be seen that the system is of a 120 flexible character, adapted for use under practically any set of conditions and for different purposes. After it has been initially determined what the proper ratio is to be, practically no skill is required of the attendant, it being only necessary for him 125 to vary the volume of the mixture consumed 130

and this by simply regulating the flow of the gas which is under pressure.

I desire to point out especially that my system is capable of use in handling fluids other than gas and air such, for example, as oil and steam, and that the number of elements capable of being handled is not limited to two. Thus, if it should be desired to combine with the mixture of air and a lean producer gas, an enriching gas, this can readily be accomplished through the use of an additional series of impeller vanes; that it is not essential that the gas as distinguished from the air be under pressure, it being obvious that the automatic operation may be accomplished by either of the gases under pressure for acting positively upon the other to control the ratio between the two elements to constitute the mixture.

In the subjoined claims, the word "positive" as used, refers to the character of the movement imparted to the air or other fluid in the outer passageway by the direct action of the outer blades thereon as distinguished from an induced flow produced by a current under pressure; and the terms "gas" and "air" are employed for the sake of convenience and not by way of limitation.

While I have herein illustrated and described a construction in which one fluid body under pressure is utilized to effect the movement of another fluid body not under pressure through the medium of an impelling device embodying turbine blades adapted to receive the impact of the fluid body under pressure, it is contemplated that the impeller with its two series of blades may be actuated by means deriving its power from a source other than a fluid body under pressure.

I claim as my invention:

1. In a gaseous fuel supply system, the combination with a source of gas supply under pressure, a gas tube communicating with said source and having a discharge nozzle, an air tube surrounding the gas tube in spaced relation with reference thereto and having an air inlet opening at its rear end, said air tube providing an annular passageway around the gas tube and a continuing passageway forwardly of said nozzle, a fan wheel comprising turbine blades disposed in the path of gas discharged from said gas tube and adapted to impart rotation to said wheel and fan blades projecting into said annular passageway and adapted upon rotation of the wheel to force into the forward passageway a volume of air in a predetermined proportion to the volume of gas discharged from the gas tube, and means for controlling the volume of the gas thus discharged.

2. In a gaseous fuel supply system, the combination with a source of gas supply un-

der pressure, a gas tube communicating with said source and having a discharge nozzle, an air tube surrounding the gas tube in spaced relation with reference thereto and having an air inlet opening at its rear end, said air tube providing a passageway forwardly of said nozzle, a fan wheel comprising turbine blades disposed in the path of gas discharged from said gas tube and adapted to impart rotation to said wheel and fan blades projecting radially into said air tube and adapted upon rotation of the wheel to force into said passageway a volume of air in a predetermined proportion to the volume of gas discharged from the gas tube, and means for controlling such volume of the gas thus discharged.

3. In a gaseous fuel supply system, the combination with a source of gas supply under pressure, a gas tube communicating with said source, an air tube surrounding the gas tube in spaced relation with reference thereto, a fan wheel comprising turbine blades disposed in the path of gas discharged from said gas tube and adapted to impart rotation to said wheel and fan blades projecting into said air tube and adapted upon rotation of the wheel to cause a proportional volume of air to move forwardly for intermixture with the gas discharged from the gas tube.

4. In a gaseous fuel supply system, the combination of an air tube and a gas tube concentrically arranged, the gas tube being of substantially smaller dimensions than the air tube and terminating at a point within the forward end of the air tube, means for compressing one of said gases, and a fan wheel adapted to be driven by the gas under pressure to force a quantity of the other gas into the forward end of the air tube.

5. In a gaseous fuel supply system, the combination of an air tube and a gas tube concentrically arranged, the gas tube being of substantially smaller dimensions than the air tube and terminating at a point within the forward end of the air tube, means for compressing one of said gases, and a fan wheel adapted to be driven by the gas under pressure to force a quantity of the other gas into the forward end of the air tube, the latter providing a passageway having a peripheral surface forming a Venturi tube.

6. In a gaseous fuel supply system, the combination of a pair of concentric tubes one substantially larger than the other, means for supplying air and gas to the respective tubes, one of said gases being under pressure, and a device actuated by the discharge of the gas under pressure to effect the positive movement of the other gas in a predetermined proportional volume.

7. In a gaseous fuel supply system, the combination of a pair of concentric tubes one substantially larger than the other, means for supplying air and gas to the re-

- 5 spective tubes, one of said gases being under pressure, a device actuated by the discharge of the gas under pressure to effect the positive movement of the other gas in a predetermined proportional volume, and means for controlling the volume of the gas under pressure acting upon said device. 70
- 10 8. A gas burner comprising, in combination, a pair of concentric tubes, one of which is substantially larger than the other and provides an annular passageway, a nozzle for the inner tube mounted in slightly spaced relation forwardly thereof, a fan wheel mounted between said inner tube and said
- 15 15 nozzle for rotation by fluid under pressure discharged from said gas tube into said nozzle, said wheel being adapted to move positively a proportional quantity of a second fluid forwardly in said passage for mixture 20 with the fluid discharged from said nozzle. 80
- 20 9. A gas burner comprising, in combination, a pair of concentric tubes, one of which is substantially larger than the other and provides a passageway for air, means for 25 supplying gas to the inner tube under pressure, a nozzle for the gas tube mounted in slightly spaced relation forwardly thereof, a fan wheel mounted between said gas tube and said nozzle for rotation by gas under
- 30 30 pressure discharged from said gas tube into said nozzle, said wheel being adapted to move positively a predetermined quantity of air forwardly in said passage for mixture with the gas discharged from said nozzle, said 35 gas tube having in its forward end a disk having ports for directing the gas against said wheel to actuate it, and means for controlling said ports. 100
- 35 10. A gas burner comprising, in combination, an air tube communicating at its rear end with the atmosphere, a gas tube located centrally within said air tube and forming a passageway around it for the air, means for supplying gas under pressure to said gas 40 tube, a fan wheel adapted to be actuated by the gas discharged from said tube and operable to move positively a predetermined volume of air through said passageway, and means for controlling the flow of gas and thereby the volume of the mixture discharged for combustion. 105
- 45 11. A gas burner comprising, in combination, an air tube communicating at its rear end with the atmosphere, a gas tube located centrally within said air tube and forming a passageway around it for the air, means for supplying gas under pressure to said gas tube, a fan wheel adapted to be actuated by the gas discharged from said tube whereby to move positively a predetermined proportional volume of air through said passageway, and means for controlling the flow of gas and thereby the volume of the mixture discharged for combustion, said means comprising a disk 50
- 55 mounted in the forward end of the gas tube and having one or more ports for directing a jet of gas against said wheel, and a valve member manually operable to control the flow of gas through said port. 70
- 60 12. A gas burner comprising, in combination, an air tube communicating at its rear end with the atmosphere, a gas tube located centrally within said air tube and forming a passageway around it for the air, 75 means for supplying gas under pressure to said gas tube, a fan wheel adapted to be actuated by the gas discharged from said tube and operable to move positively a predetermined volume of air through said passageway, and means for controlling the flow of gas and thereby the volume of the mixture discharged for combustion, said means comprising a disk mounted in the forward end of the gas tube and having one or more 80 ports for directing a jet of gas against said wheel, and a valve disk having a plurality of ports therein adapted to permit the discharge of a variable quantity of gas and having means whereby it may be manually 85 operated. 90
- 65 13. In a device of the character described, the combination of a fan wheel for controlling the intermixture of air and gas in a predetermined proportion, means for controlling the flow of a gas under pressure against said wheel to actuate it comprising a pair of disks each having ports adapted for registry so as to vary the volume of the gas discharged therethrough, one of said 95 disks having a stem, and a hand wheel on said stem. 100
- 70 14. In a device of the character described, the combination of a fan wheel, and means for rotatively supporting said wheel in the path of the gas under pressure whereby to actuate it and move positively a predetermined proportional volume of another gas for mixture therewith. 105
- 75 15. In a device of the character described, the combination of a casing, a tube discharging into said casing, a fan wheel adapted to be rotated by gas under pressure to impel positively a predetermined quantity of the other gas with which it is to be mixed for combustion purposes, and means for rotatively supporting said wheel comprising an axial stem, and a member mounted within the forward end of said tube providing a support for said stem. 110
- 80 16. The combination of a compressor, means providing a passageway for an element under pressure discharged from said compressor, means providing an annular passageway around the first passageway, and an impelling device having vanes located in said annular passageway and turbine blades located in the first passageway and adapted to receive the impact of the element under pressure prior to its dis- 115
- 85 120
- 90 125

charge for effecting the rotation of the impelling device.

17. In combination, a discharge tube for an element under pressure, means providing a passageway around said tube for a second element, an impelling device actuated by the element under pressure to move positively a second element through said passageway, and means for varying the force 10 of the impact of the first element against the impelling device.

18. The combination of a conductor communicating with an element under pressure, a second conductor concentric with the first

15 conductor and communicating with a source of supply of a second element, and an impelling device operable in one of said conductors and arranged to be actuated by the element under pressure in its passage 20 through the other conductor.

19. The combination of a conductor communicating with an element under pressure, a second conductor concentric with the first conductor and communicating with a source 25 of supply of a second element, and an impelling device operable in one of said conductors and arranged to be actuated by the element under pressure in its passage through the other conductor, the outer conductor being arranged to extend forwardly 30 from the inner conductor and providing a mixing chamber forwardly thereof and in the form of a Venturi tube.

20. In a fluid fuel supply system, the 35 combination of a pair of concentric conductors one of which is substantially larger than the other so as to provide a passageway therebetween, means for supplying two elements to be mixed to the respective conductors, and rotary means operating in each 40 of the conductors adapted to act upon the element supplied thereto and effect its forward movement in measured flow for subsequent intermixture with the element in the 45 other conductor.

21. A gaseous fuel supply system, comprising a pair of concentric tubes one of which is of greater diameter than the other so as to form an annular passageway between the tubes, each of said tubes communicating with a source of supply of a gaseous element, and means mounted for rotation in the respective tubes and operable to effect the movement of said elements 50 in a predetermined ratio while confined by their respective tubes and independently of the intermixture of the elements.

22. In a gaseous fuel supply system, means 60 providing separate passages for gaseous elements to be mixed, and means for controlling the flow of the gaseous elements through their respective passages comprising an impelling device having turbine blades disposed in one of said passages and fan

blades disposed in the other one of said passages.

23. In a fluid fuel supply system, the combination with means for supplying gas under pressure, of means for providing a pair of passages arranged to discharge 70 into a common chamber for intermixture and combustion, and means for effecting the measured flow of air and gas through said passages comprising a turbine adapted to be subjected to the force of the gas under pressure and a fan operable by the turbine to force air through the other one of said passages in measured flow.

24. In a gaseous fuel supply system, the combination with means for supplying a 80 gaseous element under pressure, a pair of passages arranged to discharge into a common chamber, said passages being tapered in the direction of flow of the gases, and means for effecting the measured movement 85 of air and gas while separately confined through said passages into said chamber, the last mentioned means being operable by the force of the gas under pressure.

25. In a gaseous fuel supply system, the combination with means for supplying a gaseous element under pressure, and means providing a mixing chamber, of a pair of 90 passages discharging into said chamber, said passages being tapered in the direction of flow of the gases, and means for effecting the measured movement of air and gas while separately confined through said passages 95 into the combustion chamber, the last mentioned means being operable by the force 100 of the gas under pressure and comprising a rotary member having fan and turbine blades disposed respectively in the path of the air and gas flowing to said passages.

26. A gas burner having a pair of annular passages one within the other, and rotary means for effecting the measured flow 105 of two gaseous elements separately through said passages comprising two series of blades, the blades of one series being adapted 110 when subjected to a gaseous element under pressure to impart movement to the blades of the other series whereby to effect the positive movement of the other gaseous element.

27. A gas burner having a pair of annular passages one within the other, and a rotary element including two means located 115 respectively in the two passages and both operating upon gaseous elements while separately confined in the respective passages to 120 effect their movement in measured flow for subsequent intermixture.

28. The method of supplying for combustion a fluid fuel consisting of two or more 125 separate elements, which consists in conducting the elements to a common point of intermixture by effecting the independent movement of each element in a measured

flow while confining it from the other element or elements, thus maintaining it in its innate state until discharged in the pre-determined proportion at the said point of 5 intermixture.

29. An impeller for a fluid fuel supply means, having two sets of vanes or blades of which one set are turbine blades adapted to receive the impact of a fluid body under

pressure whereby to impart rotary move- 10 ment to the impeller, the other set of blades being fan blades adapted to engage another fluid body not under pressure to propel it forwardly for mixture with the fluid body under pressure.

In testimony whereof, I have hereunto set my hand.

15 THERON L. HILES.
